APPARATUS FOR LOCATING WATER BEARING STRATA IN BORE HOLES OF FLOWING WELLS

Filed Sept. 2, 1924

UNITED STATES PATENT OFFICE.

FREDERICK W. HUBER, OF RIVERSIDE, CALIFORNIA.

APPARATUS FOR LOCATING WATER-BEARING STRATA IN BORE HOLES OF FLOWING WELLS.

Application filed September 2, 1924. Serial No. 735,330.

To all whom it may concern:

Be it known that I, FREDERICK W. HUBER, a citizen of the United States, residing at Riverside, in the county of Riverside, State 5 of California, have invented a new and useful Apparatus for Locating Water-Bearing Strata in Bore Holes of Flowing Wells, of which the following is a specification.

This invention relates to a method for locating water bearing strata in bore holes in oil or gas bearing formations and the main 10 object of the invention is to provide a means and method whereby the location of such water bearing strata may be positively determined without interrupting the operation 15 of the well.

In the operation of oil wells it often occurs that after the oil has been flowing for some time either under natural pressure or with 20 the assistance of pumping, there is a tendency for water (so-called edge water) to enter the well from water bearing strata adjacent to the bore hole, this tendency increasing as the gas pressure in the well diminishes and often resulting eventually in the 25 abandonment of the well. In some cases, also, it is not possible to start production of oil, because of flow of water into the well. My invention provides for determining the 30 location of water bearing strata while the well is in operation or before it starts into operation so that steps can be taken promptly to cement out such strata so as to exclude water from entering the well from 35 such strata and to start or maintain the well in productive operation.

My invention provides for introduction within the bore hole of a flowing well a means for producing at any one of the desired 40 levels in the well a zone of fresh water or water of relatively different salinity and further introducing into the well a means for measuring the salinity of the liquid adjacent to such fresh water zone in such manner 45 that any variation of such salinity due to proximity of the strata bearing salt water will result in a corresponding variation in electrical measurement thereby determining the location of the water bearing stratum. 50 The salinity of the liquid is preferably measured by introducing electrode means, connected to a source of (preferably alternating) current of substantially uniform

voltage into the well in such manner that such electrode means are exposed to the 55 liquid in the well and measuring the resistance of the liquid so exposed to the electrode means in any suitable manner.

The accompanying drawings illustrate the 60 manner in which my invention may be carried out and referring thereto:

Fig. 1 is a diagrammatic vertical section of a well with the measuring appliances in place therein.

Fig. 2 is a section of the exploration tube 65 and a side elevation of the resistance measuring appliance with the electrical circuits therefor shown diagrammatically.

Fig. 3 is a vertical section of the electrodes. 70

Referring to Fig. 1 a well casing is shown at 1, said casing being assumed to constitute the "oil string" which extends down into the oil sands and which is perforated in the usual manner as indicated at 2 for inflow of 75 oil. 3 indicates the "water string" which is assumed to be cemented in the usual manner so as to shut off all water strata above the oil sands, and casing 1 is further provided at its upper end with the usual means for carrying off the oil for example through delivery pipe 4.

The measuring means used according to my invention comprises a conductor cable 5 or self supporting cable means which is 80 provided with electrodes 6 and 7 at its lower end and is flexibly connected at its upper end to a suitable measuring circuit as hereinafter described. This conductor cable 5 carrying the electrode, is mounted within 85 a vertical exploration tube 8 which is formed as a string of suitable tube sections in the usual manner in the art so as to enable it to reach from the top of the well down to the level of the oil sands. This 90 tube may be supported by any suitable elevator means such as indicated at 10 so as to be raised and lowered at will and if necessary is passed through a stuffing box 13 in the casing head 14 in such manner 95 that the lower end of the tube member may be raised and lowered throughout the height represented by the perforated portion of the oil string. The cable 5 is also mounted for vertical movement within the pipe 8, for 100 example by means of a sleeve 16 mounted 105

on said cable and sliding through a stuffing box 17 on the head 18 at the upper end of said pipe 8. Said head 18 may be provided with a flexible pipe connection 20 leading 5 to a source of supply of fresh water or water of low saline concentration. Electrodes indicated at 6 and 7 may be mounted in any suitable manner for example within a cylinder 9 which may be of insulating 10 material, the electrodes in any case being insulated from one another and being mounted a definite distance apart and the cylinder being open and preferably being open at both ends so as to allow free access 15 of liquid to said electrodes. The said electrodes 6 and 7 are connected respectively to wires or conductors 22 and 23 within the said cable 5. The conductors 22 and 23 are preferably formed as steel wires or cables, 20 for the sake of strength and in that case are self-supporting, being either embedded in insulation to form a single conductor cable or being separately insulated and extending side by side to form two conductor 25 cables.

Any suitable circuit means may be provided for applying the electric current or potential to the wires leading to the electrodes so as to measure the resistance of the 30 medium presented between the electrodes, for example, as shown in Fig. 2, said electric measuring means may comprise a Wheatstone bridge 21 of usual construction, which is connected to a source of current or electric potential described below and to the circuit 35 wires 22 and 23. It is essential to the present invention that alternating current should be used in measuring the electrical resistance so as to avoid errors which would result from polarization in case direct current 40 were used, and it is also important that no ground connections should be present, and in order to satisfy these requirements 45 I prefer to use as a source of current a transformer whose primary winding 15 is connected to any suitable alternating current supply circuit, either single phase or poly-phase, and whose secondary winding 24 is connected by wires 25 and 26 to opposite 50 terminals of the Wheatstone bridge 21. The intermediate terminals of the Wheatstone bridge are connected in the usual manner to a null point indicator 27 which is of a type adapted for operation by alternating current. Said null point indicator 55 may be provided with energizing circuit connections 28 and 29, including resistance or lamp 30, for the field magnet coil thereof, so as to apply say 110 volts to such coil, to 60 produce a magnetic field which operates upon an armature coil connected by circuit wires 31 and 32 to the intermediate terminals of the Wheatstone bridge in the usual manner of such alternating current measuring 65 means. Any other electrical measuring

means, responsive to alternating current may, however, be used. The transformer used may be of the iron core type, transforming for example from 110 to 6 volts, the latter voltage being applied to the wires 70 leading to the electrode means. By maintaining only about 6 volts in the lines leading to the electrodes I ensure operation of the system even when the cable insulation has become damaged by oil or otherwise 75 as long as there is no actual short circuit.

In order that the electrode means shall operate effectively under the conditions existing in the column of liquid in the test operation as hereinafter set forth it is necessary 80 that the surface of the electrodes which are in contact with the liquid not be wetted by oil but only by water and saline solutions. For this purpose I have found it desirable to coat the surface of the metal body 85 or conductors forming the electrodes with a gelatinous substance and I have found that either gelatinous silica or agar may be used advantageously for this purpose. The gelatinous silica is however only applicable 90 to platinum or gold electrodes or to their acid resisting alloys. To coat such an electrode I allow water glass of about 1.15 sp. gr. to harden in a thin film upon the electrode and then immerse it in a very dilute 95 solution of mineral acid, which in the course of a few hours will form a gelatinous coating of silicic acid. This is then washed free of electrolytes and kept in a water saturated atmosphere until ready for use. 100

With the baser metals such as nickel (which I prefer to use in actual field work) I simply coat the cleaned electrode surface with a thin film of agar dissolved (dispersed) in hot distilled water, by dipping the electrode in the agar infusion and allowing to set, repeating the dipping and setting until a uniform and thin film is obtained over the entire electrode surface. The electrode after the agar has set (forming a stiff, jelly-like mass), is kept in water until wanted for use. It is also of advantage to first cover the cleaned electrode with a fine cambric cloth and then saturate this cloth with hot agar infusing and building up on 110 this covering a fine glaze of set agar. It is also of advantage, for particularly severe usage, to harden the agar by a hardening agent such as formaldehyde or alum. But this is generally not necessary. 115

The operation of the invention is as follows:

Assuming that a flowing oil well has been in producing operation and that the presence of water with the oil produced indicates intrusion of water into the well, the location of the water bearing stratum or strata is determined by inserting the measuring device above described into the oil well and operating it in the following manner. The 120 125 130

exploration tube 8 having been brought to position, for example with its lower end adjacent the bottom of the "oil string", fresh water is forced down through said pipe so that said pipe and the lower portion of the "oil string" become filled with fresh water, or water of low saline concentration and by gradually raising the pipe 8 while continuing to force fresh water therethrough the oil 10 may be completely displaced from the lower or perforated portion of the oil string, forming a column of fresh water, or water of low saline concentration, in contact with the oil sands supplying the well. The flow of oil 15 from the well is then preferably shut off, so as to maintain a static condition in the liquid column in the well as far as possible. I also prefer to maintain a hydrostatic pressure in the water supply pipe 8 sufficient to 20 just balance the fluid pressure in the well, so as to provide substantially a static column of liquid in the well and permit the diffusion of salt from surrounding water sands to take place even while no water is flowing from the 25 sand. If at this time there is present a water bearing stratum adjacent the perforated portion of the oil string and adjacent this fresh water column there will be diffusion of salt from such water stratum into the body of 30 fresh water in said column directly opposite such water stratum, resulting in a zone of relatively high saline concentration adjacent the stratum bearing salt water. The said water column may then be explored by lowering 35 the pipe 8 to different positions so that the lower end of said pipe is presented at different levels in said column and after each of said lowering operations the measurement of saline concentration at or adjacent to the 40 lower end of the pipe is made by means of the electrical devices above described, the cable 5 being assumed to be in position to cause the electrodes 6 and 7 to be exposed to the liquid directly below the lower end of the 45 pipe 8, and the resistance of the liquid between said electrodes being then measured by operation of the Wheatstone bridge in well-known manner or by any other suitable device for measuring electrical resistance. 50 While the pipe 8 is being brought to position or is being lowered to the bottom of the well the carrier member 9 for the electrodes 6 and 7 may be withdrawn within said pipe (by raising sleeve 16 and cable 5) so as to 55 be protected and said carrier member may be lowered below the lower end of the pipe only when measurement is to be made. In some cases I prefer to momentarily relieve the hydrostatic pressure on the water supply tube 60 8 just prior to or simultaneously with each conductivity measurement so as to cause the liquid in the well adjacent the lower portion of such tube to be forced upwardly within the same a short distance and ensure that the 65 electrodes are surrounded by such liquid rather than by fresh water from the water supply tube. By making a series of measurements at different levels throughout the range of vertical heights represented by the perforated portion of the oil string, and plotting the resistance measurements so obtained at various depths, the depth of any stratum through which salt water is penetrating the well will be indicated by a corresponding 70 low point in the resistance curve. The position of the water bearing stratum or strata having been determined in this manner the proper steps can be taken to seal or cement off such water bearing stratum from the well so as to enable the well to continue in operation in the production of oil. 75 Alternatively to the above described method of operation my invention may be carried out as follows: The pipe 8 having been lowered to near the bottom of the oil string, sufficient fresh water is passed through said pipe to displace the oil and salt water from only the lower portion of the oil string adjacent the lower end of pipe 8, and a resistance reading is then taken as above described, the electrodes 6 and 7 being lowered slightly below the pipe 8 for that purpose, and the column of liquid being preferably 80 preserved in a static condition during such measurement, by shutting off the flow of oil from the well and balancing the pressure by the hydrostatic head in the water supply pipe as above described. In some cases the hydrostatic pressure in the tube 8 may be 85 momentarily relieved at the time of making a conductivity measurement, for the purpose above described. The pipe 8 is then raised a suitable distance and another reading 90 taken and this operation of successive elevation of the pipe and resistance reading being continued until the lower end of the pipe 8 reaches the upper limit of the perforated portion of the oil string. In this case, as before, the presence of any water bearing 95 stratum will be indicated by an increase in conductivity or decrease in resistance of the liquid opposite such stratum by reason of diffusion of salt into the zone adjacent such stratum. This method of operation last described however has the advantage that the 100 measurement is made immediately after the introduction of fresh water at the measured part of the liquid column so that more uniform as well as more accurate results are obtained in some cases. In some cases, when the water entering the bore hole from the water stratum has relatively low salinity, it 105 will be desirable to introduce into the well (instead of fresh water) water of relatively high salinity, the reading for a zone opposite such a water stratum thus indicating relatively high resistance, and in general my invention provides for establishing in 110 the bore hole a water column of different saline concentration from that of the water 115 120 125 130

in the water bearing stratum to be located, and then determining the location in such a water column of any zone differing in salinity from the normal salinity of such water column.

The novel electrode described herein is claimed in a copending case 756,156, filed December 15, 1924.

What I claim is:

- 10 1. In combination with an oil well a pipe independent of the oil well casing, extending into said well and provided with means for passing water therethrough into the well, means for raising and lowering said pipe
- 15 15 insulated conductor means extending through said pipe and provided with electrodes adapted to be exposed to the liquid in the well, and electrical circuit means connected to said conductor means and provided
- 20 20 with means for measuring the resistance of the liquid between said electrodes.
- 25 2. An apparatus as set forth in claim 1 in which said insulated conductor means is movably mounted in a vertically movable pipe through which it extends, to permit

of the electrode means being withdrawn within or projected below said pipe.

3. An appliance for measuring the resistivity of the liquid at different levels in a well, comprising a vertically movable pipe, 30 independent of the well casing, such movable pipe being provided with means for forcing water therethrough, insulated conductor means extending through said pipe and provided with electrodes adapted to be 35 exposed to the liquid in the well, and electrical circuit means connected to said conductor means and provided with means for measuring the resistance of the liquid between said electrodes. 40

4. A combination as set forth in claim 3 in which said insulated conductor means is movably mounted in the pipe through which it extends, to permit of the electrode means being withdrawn within or projected below 45 said pipe.

In testimony whereof I have hereunto subscribed my name this 21st day of August 1924.

FREDERICK W. HUBER.
